UNITED STATES PATENT OFFICE.

NEWIEL J. WILLIS, OF CAMBRIDGE, MASSACHUSETTS.

SHUTTLE FOR LOOMS.

SPECIFICATION forming part of Letters Patent No. 225,673, dated March 16, 1880.

Application filed August 9, 1879.

To all whom it may concern:

Be it known that I, NEWIEL J. WILLIS, of Cambridge, in the county of Middlesex and State of Massachusetts, have invented a new and useful Improvement in Shuttles for Looms, 5 of which the following is a specification.

The object of this improvement is to effectually prevent all splitting or splintering of the shuttle near its ends, even when wood of an 10 inferior quality is used.

The invention consists in a wooden shuttle provided with a covering composed of two or more layers of cloth, or cloth and paper-pulp, saturated with the following compounds, viz: 15 Venice turpentine, glue, linseed-oil, shellac, lamp-black, and black lead in equal parts, and a somewhat smaller proportion of white vitriol. The sheets, after being saturated, are laid together and passed, while still hot, between iron rollers, which firmly paste the sheets 20 together. The sheets are then ready to be applied as a covering to the shuttle, and, thus applied, render it hard and tough to a remarkable degree and impossible to chip or splinter.

25 In the accompanying drawings, Figure 1 shows a shuttle provided with my improved covering, broken out so as to exhibit the layers. Fig. 2 is a transverse section of the same.

In this case a paper-pulp layer, *a*, is laid between two cloth layers, *b b*. 30

There may be two or more layers of cloth or cloth and paper-pulp saturated with the above compound.

Of the ingredients mentioned above the white vitriol may be omitted, and any oil or 35 oily substance substituted for the linseed-oil, to prevent cracking.

Having thus fully described my improvement, I do not claim, broadly, a covering for a shuttle; neither do I claim the above compound for any other purpose or use; but 40

What I claim, and desire to secure by Letters Patent, is—

A shuttle for looms having a body composed of wood provided with a covering consisting of two or more layers of cloth or cloth and paper-pulp saturated with the following compound, viz: Venice turpentine, glue, linseed or other oil, shellac, lamp-black, and black lead, with or without an admixture of 45 white vitriol, substantially as and in the proportions specified. 50

NEWIEL J. WILLIS.
